(57) **CLAIM**

The ornamental design for a handle for a gun cleaning kit, as shown and described.

DESCRIPTION

FIG. 1 is a frontal isometric view of my new handle for a gun cleaning kit;

FIG. 2 is a top plan view thereof;

FIG. 3 is a side elevational view thereof, the opposite side comprising a mirror image;

FIG. 4 is a bottom plan view thereof;

FIG. 5 is an end view taken from the left of FIG. 3; and, FIG. 6 is a view of the end opposite that of FIG. 5, taken from the right of FIG. 3.

The broken lines in FIG. 1 are included for the purpose of illustrating a portion of the handle for firearm maintenance that forms no part of the claimed design.
